CLOSURE ACTUATING MECHANISM

Robert H. Hummert, Dayton, Ohio, assignor to Standard-Thomson Corporation, Dayton, Ohio, a corporation of Ohio

Application August 29, 1952, Serial No. 306,990

2 Claims. (Cl. 292—265)

This invention relates to a closure actuating mechanism or stay bar assembly for use with a projected type of window or awning type of window, although not necessarily so limited.

In projected type of window, it is quite desirable to actuate the window into a position such that both the inside and the outside of the window may be washed or the window may be reglazed from the inside without removing the window sash. With the use of conventional operators, the outward swinging movement of the projected window sash is limited, so that it is inconvenient and for all practical purposes impractical to attempt to wash the outside of the window from the inside.

An object of this invention is to provide a projected type of window actuated by a stay bar assembly that may be detached from the window, so as to permit the window to be actuated beyond the operative range of the stay bar assembly into a position such that both sides of the window may be washed from the inside without detaching or removing the window sash from the window frame or window opening.

Another object of this invention is to provide a removably mounted stay bar assembly for a window wherein the stay bar assembly consists of two pivotally connected members, one of which is removably attached to the window and the other is provided with a plurality of notches adapted to hold the window open in various angular positions, as will appear more fully from the description that follows.

Other objects and advantages reside in the construction of parts, the combination thereof and the mode of operation, as will become more apparent from the following description;

Referring to the drawings,

Figure 1 is a perspective view of a window shown in one open position.

Figure 2 is another perspective view of the window shown in Figure 1, showing the stay bar actuator disconnected from the window, so that the window may be moved beyond the operative range of the stay bar actuator, so that the window may have the outside washed from the inside of the window.

Figure 3 is a fragmentary enlarged side elevational view of the actuator mechanism with parts of the window and the window frame shown in cross section.

Figure 4 is a top plan view of the actuator mechanism shown holding the window sash in closed position, parts of the window being shown in section and broken away.

Figure 5 is a cross sectional view taken substantially on the line 5—5 of Figure 4, without disclosing the brackets.

Figure 6 is a fragmentary view of a pivotal attachment for slidingly mounting the top of the movable window frame or closure in a channel in the main frame.

In the drawings, the reference character 10 designates a frame of a window provided with a closure 12 that is pivotally mounted on a pair of brackets or arms 14, only one of which has been shown. The brackets 14 are piv-

2

otally attached at 16 to the stationary window frame and pivotally attached to the window sash or closure 12 near the center thereof. The closure 12 is also provided with a pivotal attachment to a member mounted for sliding movement in the slot 18, as will appear more fully later.

The pivotal mounting of the top of the window closure has been shown in Figure 6, wherein a bracket 20 is attached to the top of the window closure by screws 22. 10 A slotted member 24 is fixedly attached to the frame. The window frame is provided with a vertically disposed slot or groove 32 underlying the slot 18 in member 24. The slot in member 24 overlies the groove 32. The outer surface of member 24 is preferably flush with 15 the adjacent portion of the window frame. A slidably mounted rivet 26 is attached to a flange 28 of the bracket 20 and supports a washer 30 located in the channel 32 underlying the slotted member 24, as best seen in Figure 6. As the lower portion of the window sash 12 swings 20 outwardly, the brackets 14 have their upper ends projecting outwardly and the top of the window is lowered. The rivet 26 then slides downwardly in the slot in member 24. It may be lowered into a horizontal position, as shown in Figure 2, when the pivot, including the 25 rivet 26, is in the lowermost position of the slot in member 24.

As may best be seen by referring to Figures 3 and 4, the movable window sash or closure 12 is provided with two brackets 40 and 40a, the bracket 40 having a vertically disposed slot 42 and the bracket 40a having an aperture 42a. A stay bar assembly 50 is removably attached to the brackets 40 and 40a. This stay bar assembly includes a comparatively short bar or link 52 provided with a cylindrical cavity or recess 54 adjacent one 35 end thereof. This cylindrical cavity is provided with a shoulder against which a compression spring 80 is seated. This spring 80 surrounds a reduced portion 70 of a pin 72. The pin 72 terminates in a knurled cylindrical head 74. A kerfed nut 58 threadedly engages the threads 56 40 on the end of the reduced portion 70. This nut 58, having a cylindrical perimeter, is normally positioned in the aperture 42a in the bracket 40a.

The spring 80 biases or urges the pin 72 to the right, as viewed in Figures 4 and 5, so as to hold the cylindrical nut 58 in the aperture 42a in the bracket 40a. In order to remove link 52 from the sash 12, it is merely necessary to grasp the knurled cylindrical portion 74 of the pin 72 and pull it toward the left, as viewed in Figures 4 and 5, to compress the spring 80, so as to cause 50 the nut 58 to be retracted into the cylindrical cavity 54 to permit removal of the link from the brackets 40 and 40a. The link 52 may be connected to the brackets by again retracting the nut 58 into the recess 54, so as to permit the insertion of the pin 72 into the slot 42 in the bracket 40, and when the nut 58 is aligned with the aperture 42a in the bracket 40a, the pull exerted upon the cylindrical portion 74 may be released, so as to permit the link 52 to lock in position.

The bar 52 has pivotally attached thereto a notched 60 bar 82 by means of a pivot 84. The notched bar 82 is provided with a plurality of notches 86 on the under side thereof, adapted to engage the margin of an aperture in a bracket 90 attached by suitable screws 92 to the window sill 94. The outer end of the bar 82 is 65 provided with a suitable handle 100 for use by the operator in actuating the stay bar assembly. In closing the window, the bar 52 projects through the aperture in the bracket 90, so as to permit the pivotally mounted notched bar 82 to be actuated at right angles about the pivot 84 into the position shown in Figure 4, at which time the bar 82 is held in position by a stop 102. The length of the bar 52 depends upon the width of the window

sill. The length is preferably such that it extends from the window through the bracket 90 a distance sufficient to lock the window sash in closed position when the bar 82 is adjusted into the position shown in Figure 4.

The bar 82 and the notches therein are preferably so dimensioned that the window sash may be adjusted into any suitable open position for ventilation. However, it is not practical by the use of the window sash actuator to actuate the window sash into the horizontal position shown in Figure 2. That being the case, the actuator bar assembly is detached from the closure by merely pulling upon the knurled head 74 of the pin 72 to disengage the brackets 40 from the actuator. The window sash 12 may then be manually adjusted into the position shown in Figure 2.

In the event a screen is used on the inside of the window sash, it is merely necessary to provide an opening or passage in the lower margin of the screen frame for the actuating mechanism, consisting of the bars 52 and 82. By this arrangement, it is possible to actuate the closure from open position into closed position, or vice versa, without removing the screen.

Although the window sash has been shown as consisting of a single window pane, it is not necessarily so limited. Furthermore, the actuator bar assembly may be used with any other suitable type of closure, as for example, a metallic closure, used in closing any type of opening.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A stay bar assembly for use in actuating a pivotal closure mounted in a fixed frame, a closure mounted for movement beyond the operative range of the stay bar assembly, said stay bar assembly including a pair of spaced apart bracket members fixedly attached to one margin of the closure, said margin being in spaced relation from the pivot points about which the closure is adjustable, one of said bracket members being provided with an aperture therein, the other of said bracket members having a slot therein axially aligned with the aperture of said first bracket member, an actuator bar, the actuator bar having two portions, there being a longer portion and a shorter portion, the portions being pivotally attached one to the other, there being an end of the shorter portion disposed between the bracket members, said end of the shorter portion of the actuator bar being provided with a cavity extending transversely therein

and aligned with the aperture and the slot of the brackets, a pin extending through the cavity of the shorter portion of the actuator bar and having a head exterior of the cavity, a spring within the cavity and encircling the pin, a nut attached to the pin opposite the head thereof, the nut retaining the spring within the cavity of the shorter portion of the actuator bar, the nut being positioned within the aperture of said bracket, the head of the pin being positioned in the slot of the other bracket, a bracket attached to said fixed frame and provided with an opening therethrough, the actuator bar being movable through said opening of the last mentioned bracket, and a stop attached to the fixed frame in spaced relation from the bracket attached thereto and engageable by the longer portion of the actuator bar for retaining the position of the actuator bar.

2. A stay bar assembly for use in actuating a pivotal closure mounted in a fixed frame, a closure mounted for movement beyond the operative range of the stay bar assembly, said stay bar assembly including a pair of spaced apart bracket members fixedly attached to one margin of the closure, said margin being in spaced relation from the pivot points about which the closure is adjustable, one of said bracket members being provided with an aperture therein, the other of said bracket members having a slot therein axially aligned with the aperture of said first bracket member, an actuator bar having an end thereof disposed between the bracket members, said end of the actuator bar being provided with a cavity extending transversely therein and aligned with the aperture and the slot of the brackets, a pin extending through the cavity of the shorter portion of the actuator bar and having a head exterior of the cavity, a spring within the cavity and encircling the pin, a nut attached to the pin opposite the head thereof, the nut retaining the spring within the cavity of the actuator bar, the nut being positioned within the aperture of said bracket, the head of the pin being positioned in the slot of the other bracket, the actuator bar thus being pivotally and releasably attached to the closure.
